UNITED STATES PATENT OFFICE

WILHELM B. BRONANDER, OF MONTCLAIR, NEW JERSEY

FIRE EXTINGUISHER SUPPORT

Original application filed March 16, 1928, Serial No. 262,201. Divided and this application filed June 6, 1929. Serial No. 368,844.

This invention relates to fire extinguisher supports and this application is a division of application Serial No. 262,201, filed March 16, 1928.

More particularly stated, the invention relates to the grenade type of fire extinguisher and to a holder or support for the grenade.

This invention has for its salient object to provide a support for a grenade so constructed that the grenade can be easily and readily removed therefrom and, furthermore, so constructed and arranged that in case of fire the grenade will automatically drop, break, and dispense the fire extinguishing fluid.

Another object of the invention is to provide a bracket or holder for grenades comprising few parts and a structure that can be economically manufactured.

Further objects of the invention will appear from the following specification taken in connection with the drawing, which forms a part of this application, and in which

Fig. 1 is an elevational view of a support constructed in accordance with the invention showing a grenade supported thereby; and

Fig. 2 is a front elevation of the construction shown in Fig. 1.

The invention briefly described consists of a support for fire extinguisher grenades having means connected to a bracket or back plate for engaging and supporting the grenade. The particular supporting means illustrated consists of a saddle adapted to engage and support the grenade in a position against the bracket or back plate, fusible means being provided for releasing the grenade in case of fire.

Further details of the invention will appear from the following description.

In the particular embodiment of the invention shown, the grenade supporting means consists of a back plate or bracket 10 and a saddle pivotally associated with the bracket and so shaped as to encircle the grenade and to support the grenade in a position against the back plate or bracket.

The saddle comprises a central portion 40 adapted to fit against the curved outer surface of the grenade, the ends of the central

portion being connected as shown at 41 and 42 to arms 43 and 44 by fusible metal. The arms 43 and 44 are preferably formed of resilient material and are pressed in and snapped over pivot lugs 45 and 46 carried by the back plate or bracket 10.

From the foregoing description and from the illustration in the drawing it will be clear that the grenade will be supported in such a manner that it will rest against the back plate or bracket. In case of fire one or both of the fusible connections will melt, thus releasing the grenade which will drop and break. In case it is desired to throw the grenade at a fire the grenade can be lifted from the saddle or it can be grasped below the saddle and the saddle can be lifted thereby releasing the grenade.

The term grenade is used throughout this specification to refer to a frangible container having a fire extinguishing fluid therein.

Although one specific embodiment of the invention has been particularly shown and described, it will be understood that the invention is capable of modification and that changes in the construction and in the arrangement of the various cooperating parts may be made without departing from the spirit or scope of the invention, as expressed in the following claims.

What I claim is:

1. A support for fire extinguisher grenades comprising a bracket and a saddle carried thereby, said saddle being incapable per se of supporting the grenade; said bracket and saddle being engageable with the grenade and conjointly effective by such engagement to support the grenade, said saddle including a fusible portion connected to the bracket and effective to release the grenade under the influence of heat.

2. A support for fire extinguisher grenades comprising a bracket and a saddle carried thereby, said saddle being incapable per se of supporting the grenade; said saddle being shaped and located to partially embrace and hold the grenade in engagement with the bracket, the saddle and bracket being conjointly effective by such engagement to support the grenade, said saddle including a

fusible portion connected to the bracket and effective to release the grenade under the influence of heat.

3. A support for fire extinguisher grenades comprising a bracket and a saddle carried thereby, said saddle being incapable per se of supporting the grenade; said bracket and saddle being engageable with the grenade and conjointly effective by such engagement to support the grenade, said saddle including pivoted means and a heat controlled portion connected to the bracket and effective to release the grenade under the influence of heat.

4. A support for fire extinguisher grenades comprising a bracket and a saddle carried thereby, said saddle being incapable per se of supporting the grenade; said saddle being shaped and located to embrace and hold the grenade in engagement with the bracket, the saddle and bracket being conjointly effective by such engagement to support the grenade, a pivotal connection between the saddle and bracket, said saddle including a heat controlled portion connected to the bracket and effective to release the grenade under the influence of heat.

5. A support for fire extinguisher grenades comprising a supporting member, and a saddle movable relative thereto, arranged and positioned to partially encircle a grenade and hold the same in engagement with said member, said saddle being incapable per se of supporting the grenade; the bracket and saddle being conjointly effective by such engagement to support the grenade, said saddle including a heat controlled element connected to the bracket and effective to release the grenade under the influence of heat.

6. A support for fire extinguisher grenades comprising a supporting member, and a curved saddle movably connected thereto, arranged and positioned to partially encircle a grenade and hold same in engagement with said member, said saddle being incapable per se of supporting the grenade; the bracket and saddle being conjointly effective by such engagement to support the grenade, said saddle including a heat controlled element connected to the bracket and effective to release the grenade under the influence of heat.

7. In combination, a substantially pear-shaped grenade, a bracket plate and a curved saddle movably carried by said plate; said saddle being shaped and positioned to partially encircle and hold the grenade in engagement with said plate, and being incapable per se of supporting the grenade; the bracket and saddle being conjointly effective by such engagement to support the grenade, said saddle being vertically movable and including a heat controlled element effective to release the grenade under the influence of heat.

8. In combination, a substantially pear-shaped grenade, a bracket plate and a curved

saddle pivotally carried by said plate for movement on a substantially horizontal axis, said saddle including means arranged on destruction to render said saddle and bracket plate incapable of supporting said grenade, 70 said saddle being shaped and positioned to partially encircle and hold the grenade in position against said plate.

9. A support for fire extinguisher grenades comprising a supporting member, and a saddle pivoted to said member on a substantially horizontal axis and arranged and positioned to partially encircle a grenade and hold the grenade against said member, said saddle including a fusible means arranged on destruction to render said saddle and supporting member incapable of supporting said grenade. 75 80

10. In combination a substantially pear-shaped grenade, a bracket plate, and a curved saddle carried by said plate and shaped and positioned to partially encircle and hold the grenade in position against said plate, said saddle being incapable per se of supporting said grenade; the bracket and saddle being conjointly effective by their engagement with the grenade to support same, said saddle including a fusible portion connected to the bracket and effective to release the grenade under the influence of heat. 85 90 95

11. A support for fire extinguisher grenades comprising a bracket and a holding member carried thereby, said holding member being incapable per se of supporting the grenade; said bracket and holding member being engageable with the grenade and conjointly effective by such engagement to support the grenade, said holding member including a fusible portion connected to the bracket and effective to release the grenade 100 105 under the influence of heat.
